(57) **CLAIM**

The ornamental design of a surface cleaning head component of a vacuum cleaner, substantially as shown and described.

DESCRIPTION

FIG. 1 is a top perspective view of a surface cleaning head component of a vacuum cleaner showing our new design;
FIG. 2 is a front view thereof;
FIG. 3 is a rear view thereof;
FIG. 4 is a left side view thereof;
FIG. 5 is a right side view thereof;
FIG. 6 is a top view thereof; and,
FIG. 7 is a bottom view thereof.

The broken lines are included for the purpose of illustrating the unclaimed portions of the article and form no part of the claim.

1 Claim, 6 Drawing Sheets
